UNITED STATES PATENT OFFICE.

DESIDER ZORGO, OF MONTREAL, QUEBEC, CANADA, ASSIGNOR OF FOUR-TENTHS TO
MIKLOS SZAKACS, OF BROOKLYN, NEW YORK.

AUTOMATIC ELECTRIC TIME SWITCH.

Application filed May 13, 1926. Serial No. 108,789.

This invention relates generally to time switches, and has more particular reference to a novel type of twenty-four hour variable adjustable switch adapted to control building lights, etc.

The invention has for an object the provision of an improved time switch which will be adapted for adjustments in six-hour sectors, or any other desirable divisions. By 10 adjustments in six-hour sectors is meant, that the device is adapted to close an electrical circuit from the starting of a six-hour sector to any desired time within the six hours, thereafter opening the circuit for 15 the balance of the six hours, and so on for any six-hour sector. Of course, the principle may be extended to any other time sector, such as for example a four-hour sector.

For further comprehension of the invention, and of the objects and advantages thereof, reference will be had to the following description and accompanying drawings, and to the appended claims in which the various novel features of the invention are more particularly set forth.

Referring to the drawings forming a material part of this disclosure:—

Fig. 1 is a front perspective view of a device constructed according to this invention.

Fig. 2 is a sectional rear view of the device taken just in front of the rear cover.

Fig. 3 is a vertical sectional view, taken on the line 3—3 of Fig. 2.

Fig. 4 is a fragmentary sectional view taken on the line 4—4 of Fig. 2.

Fig. 5 is a fragmentary detail view of the front stationary dial.

Fig. 6 is a fragmentary, partly sectional view of the clutch mechanism for adjusting 40 the position of the front rotating dial.

Fig. 7 is a detail sectional view of the substantially central stationary brush.

Fig. 8 is a detail sectional view of one of the adjustable brushes mounted on the front rotating dial.

Fig. 9 is a detail front view of the stationary cam element positioned behind the front rotating dial, and upon which the adjustable brushes of the front rotating dial 50 glide thereover.

Fig. 10 is a horizontal sectional view taken on the line 10—10 of Fig. 9.

The reference numeral 10 generally indicates the casing having depending flanges 11 55 formed with apertures 12 for fastening the

device to a suitable support. The screws 13 clamp the rear wall of casing 10, the rear plate 14 of a frame formed with a front plate 15 joined to said rear plate 14 by the spacing rods 16, held by screws 17. Mounted 60 on the front face of front plate 15 is the insulation plate 18, and secured to the front face of the insulation plate is the time-sector cam element 19, formed with a vertically disposed beveled portion 19^a at the central 65 upper point, and from the lower extremity of the beveled portion leads a cam edge 19^b to the horizontal center line 19^c, thereafter joining the edge of a circular aperture 19^d. Closing the front of the casing 10 is a stationary 70 insulation material front face 20 formed with a circular dial with divisions graduated into 24 hours, with the ordinals of the scale running counter-clockwise.

A shaft 25 journaled in the rear and front 75 plates 14, and 15 is provided with a positioning collar 26 fixed thereto, and with a clutch face collar 27 also fixed thereto, and finally with an end member 28. An insulation material knob 29 is rotatable on member 28, and rigidly attached to knob 29 is a clutch face member 30, rigidly supporting the conductive dial member 31 and the front insulation material dial 32, both dial members being formed with elongated slots 33, 80 preferably four in number, and equally spaced so as to represent six-hour sectors. On the front dial 32, adjacent each elongated slot is a scale graduated into six hour divisions, such that zero on the scale aligns 90 just beneath the very bottom of the cam portion 19^a, and six on the scale aligns with the top of the cam portion 19^a, the cam element 19^b being such that the intermediate graduations correspond to the length of time necessary 95 for a theoretical point to travel along the arc of a circle from the edge 19^a to reach a point on edge 19^b when the theoretical point is traveling at the rate of one revolution per 24 hours. The spring 34 normally 100 acts to keep the clutch faces of 27 and 30 engaged.

Slidable in each of the slots 33, is a carbon brush 35 projecting from a casing 36, engaged by a casing head 37, provided with 105 an insulation knob 38, and a pointer 39. The spring 40 normally urges the carbon brush 35 outwards against the cam 19 or the insulation 18.

Fastened to the members 15, and 18 is an- 110

other brush 41 in a casing 42, having a cover 43, an interior spring 44, and a terminal connection 45.

A clock mechanism is mounted within the frames 14, and 15 and is adapted to revolve the shaft 25 once every 24 hours. Projecting from the side of the casing 10 is the winding handle 46 connected to a bevel gear 47, engaging another bevel gear 48 on a shaft 49 connected in the customary way, to a customarily operated clock-spring housed in casing 50, provided with a rear gear 51, and connected by a train of gears to the shaft 25. Another train of gears mesh in with the first train, and the last gear 52 of the second train is on a shaft 53 provided with a governor device characterized by weighted springs 54, connected with wheel 55 damped by pin 56 on the end of a lever 57 pivotally mounted on bracket 58, and urged from damping position by spring 59, against the damping action of rod 60 abutting said lever 57, and mounted threadedly engaging bracket 61, while slidable in bracket 62, the end of said rod 60 being provided with an operating knob 63.

Mounted on the top of casing 10 is an electrical socket 64, having a lead 65 to terminal 45, and the second lead 66 to the cam 19.

The operation of the device consists in the closing of the circuit between leads 65, and 66 during certain hours. The clock mechanism, first of all, is set going, which results in the revolving of the dials 31, and 32 at the rate of once every 24 hours, revolving clockwise. Due to the clutch faces between members 27, and 30, the dials 31, and 32, may be turned clockwise without effecting the shaft 25, allowing suitable setting. Each of the brushes 35 are set as desired along the slots 33 indicated by the pointers 39, against the adjacent scale. For example assume the settings shown in Fig.

1. The upper pointer 39 is set to 5 on the scale, the dials 31, and 32 being rotated by the clock mechanism as stated, and the specific brush 35 just riding up on the bevel 19^a of the cam 19, the electrical circuit being closed from lead 65 to terminal 45, brush 41, dial 31, brush 35, cam 19, and finally lead 66. After five hours the brush 35 rides off of the cam face 19^b, opening the electrical circuit, and in another hour the brush 35 of the pointer which was on the left hand side of Fig. 1, reaches the top ready to ride onto the bevel 19^a of the cam 19, but assuming this pointer to be at zero on the scale, the brush 35 will just be out of reach of the very bottom of the bevel 19^a, therefore for six additional hours the circuit will remain open. After this time has passed the pointer which was originally on the bottom side, shown in Fig. 1, reaches the top ready to ride onto the bevel 19^a of the cam 19, but

assuming this pointer to be at zero on the scale, the specific brush 35 will just be out of reach of the very bottom of the bevel 19^a, therefore for six additional hours the circuit will remain open. After this time 70 has passed the pointer which was originally on the right hand side, shown in Fig. 1, reaches the top ready to ride onto the bevel 19^a, and assuming the pointer to be set at 3 1/4, the electrical circuit will be closed, and 75 will remain closed for 3 1/4 hours, until the brush 35 rides off of cam edge 19^b.

If all the pointers were placed on six on the scales, the circuit would always be closed, and should the pointer be placed on zero 80 the circuit would always be opened.

While I have illustrated and described my invention with some degree of particularity, I realize that in practice various alterations therein may be made. I therefore reserve 85 the right and privilege of changing the form of the details of construction or otherwise altering the arrangement of the correlated parts without departing from the spirit or the scope of the appended claims. 90

Having thus described my invention, what I claim as new, and desire to secure by United States Letters Patent is:

1. In a time switch, a time rotated dial formed of an insulated front member, and a conductive rear member, both members being provided with certain radial elongated slots, a time scale adjacent said slots, brushes slidable in said slots, and provided with pointers to said adjacent scale, a time sector cam element, provided with a rear insulation member, stationarily mounted behind said dial, said brushes engageable against said cam or against said insulation member, said cam being formed with a beveled vertically disposed portion to allow said brushes to ride from said rear insulation member onto said cam, the lower extremity of said beveled portion leading into a cam edge, and a stationary brush depending from said rear insulation member, and bearing against said conductive rear member of said dial. 100

2. In a time switch, a time rotated dial formed of an insulated front member, and a conductive rear member, both members being provided with certain radial elongated slots, a time scale adjacent said slots, brushes slidable in said slots, and provided with pointers to said adjacent scale, a time sector cam element, provided with a rear insulation member, stationarily mounted behind said dial, said brushes engageable against said cam or against said insulation member, said cam being formed with a beveled vertically disposed portion to allow said brushes to ride from said rear insulation member onto said cam, the lower extremity of said beveled portion leading into a cam edge, and a stationary brush depending from said rear insulation member, and bearing against said 110 conductive rear member of said dial. 115

- conductive rear member of said dial, whereby an electrical circuit exists between said latter mentioned brush, the rear of said dial, and the slidable brushes on said dial.
- 5 3. In a time switch, a time rotated dial formed of an insulated front member, and a conductive rear member, both members being provided with certain radial elongated slots, a time scale adjacent said slots, brushes 65
10 slidable in said slots, and provided with pointers to said adjacent scale, a time sector cam element, provided with a rear insulation member, stationarily mounted behind said dial, said brushes engageable against 70
15 said cam or against said insulation member, said cam being formed with a beveled vertically disposed portion to allow said brushes to ride from said rear insulation member onto said cam, the lower extremity 75
20 of said beveled portion leading into a cam edge, and a stationary brush depending from said rear insulation member, and bearing against said conductive rear member of said dial, whereby an electrical circuit exists be- 80
25 tween said latter mentioned brush, the rear of said dial, and the slidable brushes on said dial, the circuit including the time sector cam only when said cam is engaged by 85
30 one of said brushes.
- 30 4. In a time switch, a time rotated dial formed of an insulated front member, and a conductive rear member, both members being provided with certain radial elongated slots, a time scale adjacent said slots, and 90
35 a time scale depending from a stationary member adjacent the circumference of said dial, brushes slidable in said slots, and provided with pointers to said adjacent scale, a time sector cam element, provided with a 95
40 rear insulation member, stationarily mounted behind said dial, said brushes engageable against said cam or against said insulation member, said cam being formed with a beveled vertically disposed portion to al- 100
45 low said brushes to ride from said rear insulation member onto said cam, the lower extremity of said beveled portion leading into a cam edge, and a stationary brush depending from said rear insulation member, 105
50 and bearing against said conductive rear member of said dial.
5. In a time switch, a time rotated dial formed of an insulated front member, and a conductive rear member, both members 110
55 being provided with certain radial elongated slots, a time scale adjacent said slots, brushes slidable in said slots, and provided with pointers to said adjacent scale, a time sector cam element, provided with a rear insulation member, both being stationarily mounted 115
60 behind said dial, said brushes engage-

able against said cam or against said insulation member, depending upon the position of said brushes in said slots, said cam being formed with a beveled vertically dis- 65
posed portion to allow said brushes to ride from said insulation member onto said cam, the lower extremity of said beveled portion leading into a cam edge, and a stationary brush depending from said rear insulation 70
member, and bearing against said conductive rear member of said dial.

6. In a time switch, a time rotated dial formed of an insulated front member, and a conductive rear member, both members 75
being provided with certain radial elongated slots, a time scale adjacent said slots, brushes slidable in said slots, and provided with pointers to said adjacent scale, a time sector cam element, provided with a rear in- 80
sulation member, stationarily mounted be- 85
hind said dial, said brushes engageable against said cam or against said insulation member, said cam being formed with a be- 90
veled portion to allow said brushes to ride from said rear insulation member onto said cam, the lower extremity of said beveled portion leading into a cam edge, and a sta- 95
tionary brush depending from said rear in- 100
sulation member, and bearing against said conductive rear member of said dial.

7. In a time switch, a time rotated clutch connected dial formed of an insulated front member, and a conductive rear member, both members being provided with certain radial 95
elongated slots, a time scale adjacent said slots, brushes slidable in said slots, and pro- 100
vided with pointers to said adjacent scale, a time sector cam element, provided with a rear insulation member, stationarily mount- 105
ed behind said dial, said brushes engage- 110
able against said cam or against said insulation member, said cam being formed with a beveled vertically disposed portion to allow said brushes to ride from said rear insulation member onto said cam, the lower extremity of said beveled portion leading into a cam edge, and a stationary brush de- 115
pending from said rear insulation member, and bearing against said conductive rear 120
member of said dial.

8. In a device of the class described, a time-sector cam element, comprising a main body, an inner vertically disposed beveled portion, a cam edge starting at the bottom 115
of said beveled portion, and a circular edge, joining the end of said cam edge to the top of said beveled portion, said circular edge being concentric to the said main body.

In testimony whereof I have affixed my 120
signature.

DESIDER ZORGO.
